UNITED STATES PATENT OFFICE

2,430,256

REFRIGERATOR CAR FLASHING

James S. Swann, Homewood, Ill., assignor to
Standard Railway Equipment Manufacturing
Company, Chicago, Ill., a corporation of Dela-
ware

Application February 7, 1946, Serial No. 646,054

8 Claims. (Cl. 62—17)

1

This invention relates to railroad refrigerator cars used to transport perishable commodities at a predetermined temperature. The invention is applicable particularly to cars wherein the cooling means, preferably containers for solid refrigerant, are disposed immediately below the roof of the car. The lading is supported in spaced relation to the floor by a foraminous rack. Flues, preferably associated with the side walls of the car, communicate between the cooling means and the space under the floor rack to provide a path for the circulation of air. Said path is from the cooling means downwardly through said flues through the space under the floor rack, upwardly through the lading compartment, thereby cooling the lading, and finally to the cooling means from whence the cycle is repeated.

The containers may be of any of several types, either foraminous when water ice is used, partly foraminous and partly imperforate when ice and salt is used, or wholly imperforate with drain and overflow openings.

Drip pans are provided immediately below said containers to catch the liquid therefrom and conduct the same to and into said flues. The liquid dripping from said containers onto said drip pans is subject to a certain amount of surging thereon due to service movements of the car, and consequently provision must be made to prevent such surging liquid from leaving said drip pan and falling within the lading compartment, which is one of the objects of the invention. In certain types of these refrigerator cars, the doors thereof are provided with flues which, when the doors are closed, register with the wall flues above and below the doors and conduct moisture and air therethrough to the bottom of the car. Thus when the doors are open, as when the car is being loaded, the drippage falls from the top of the doorway to the great annoyance of the persons loading the car. An object of the invention is to provide a flashing at the upper edge of the car lining and top of the flues extending over the doorways of the car to prevent the possibility of such drippage in the doorway.

It is another object of the invention to provide such flashing, either wholly upon the side wall of the car at the top of said flue, or wholly upon the adjacent edge of said drip pan, or upon cooperative parts of said flashing on both the wall and drip pan.

A further object of the invention is to provide such flashing, either for the drip pan or the car above the lining, constructed and arranged to prevent moisture from the drip pan contacting the car posts or dripping into said doorway.

2

A still further object of the invention is to provide such flashing with baffles to prevent moisture thereon from draining over the edges thereof and then moving longitudinally of said edges by capillary attraction into contact with said posts, or into said doorway or into said lading compartment.

Other objects and advantages of the invention will appear in the following detailed description thereof.

Referring now to the accompanying drawings forming part of this application and wherein like reference characters indicate like parts.

Figure 1 is a partial transverse section of a refrigerator car embodying one form of the invention.

Figure 2 is an enlarged partial cross sectional view through the drip pan showing a modification of the invention.

Figure 3 is a perspective view of the flashing employed in the modification shown in Figure 2.

Figure 4 is a side elevation of part of the flashing which extends over a doorway and flue adjacent one side thereof of the modification shown in Figure 1.

Figure 5 is a section on line 5—5 of Figure 4.

Figure 6 is a top plan view of Figure 4 showing in section the associated side wall flue, door posts and inner posts.

Figure 7 is a broken perspective view of the portion of the flashing shown in Figures 1, 4, 5 and 6 extending over the doorway.

In the drawings the general parts of the refrigerator car shown are insulated roof 2; side wall 3; floor 4; hatch 5; refrigerant container 6; side wall flues 7; foraminous floor rack 8; and space 9 between the rack 8 and floor 4. The refrigerant container 6 is positioned directly below the roof 2 and adjacent a side wall 3. A drip pan 12 is provided below the container, and a partition 14 is disposed in an upstanding position at the inner edge of the drip pan 12. The drip pan 12 and partition 14 cooperate with the roof and upper part of the side wall forming a cooling compartment about container 6, said cooling compartment having an inlet 15 between the upper edge of partition 14 and the car roof, and an outlet 17 between the outer edge of drip pan 12 and car wall adjacent flue 7. The warm air from the

lading compartment rises and enters cooling compartment through inlet 15, is cooled therein and falls by gravity through discharge opening 17 and flue 7, to space 9, whence it rises through rack 8 to the lading compartment 18.

The side wall comprises a series of spaced outer posts 25 and a series of spaced inner posts 26. Flue

sheets 28 extend between and are secured to inner surfaces of inner posts 26 and are provided with outwardly projecting panels 29 between said posts 26. Door posts 30 are shown at either side of the doorway 30' therebetween. A lining 31 is disposed flatwise against and secured to posts 26 and door post 30, thereby forming side wall flues 7 between the lining and outwardly projecting panels 29 of the flue sheets 28, and the outer edge of the drip pan 12 occurs in substantially the same vertical plane as the lining 31 but spaced slightly thereabove.

In the modification shown in Figures 1, 4, 5, 6 and 7, there is provided a flashing extending from end to end of the car and adapted to be secured to the inner posts 26, said flashing comprising a downwardly extending vertical body portion 32 which is adapted to be secured to said posts 26 between said posts and upper part of lining 31, which part of said lining is rabbeted to receive same. Said flashing also comprises a substantially horizontal portion 33 which extends inwardly and slightly upwardly over the upper edge of said lining 31 and is then bent upwardly at a greater angle forming a marginal flange 34, all as clearly shown in Figure 7. The portions 33 and 34 are continuous from end to end of the car and form a gutter at the side of the car under the outer edge of the drip pan, but the portion 32, at points on opposite vertical edges of the doorway and each post 26 is slit and the material between said slits is bent to extend upwardly, as shown at 32'. A vertically disposed angle piece is shown, having one flange 35 thereof secured flatwise to the vertically extending adjacent edges of portions 32 and 32' so that the other flange 35 extends normal thereto and acts as a baffle to prevent water dripping into said doorway or against said posts as hereinafter described.

Were it not for these baffles 35 water in said gutter running over the downwardly extending portions 32 might, because of surging due to service movements of the car, or capillary attraction, move longitudinally along said portion 32 or elsewhere until in contact with a post, or over the lading space and drip thereto, either of which, of course, is very undesirable. Also any moisture from the drip pan flowing into portions 33 and 34 will be effectively prevented by the portions 32' from contacting posts 26 or dripping into said doorway. As shown in Figure 1, drip pan 12 may have a counterflashing extending from the outer lower edge thereof into said gutter-like portion 33-34 to direct liquid from the drip pan thereto. In the modification shown in Figures 2 and 3 the drip pan 12 is provided along its outer edge with a flashing 40, which underlaps the outer margin of said drip pan, and the outer margin of said flashing 40 is bent downwardly, as at 41, in overlapping relationship with lining 31. The containers 6 are longitudinally spaced along the upper outer portion of the car, and each container is provided with a drip pan 12 thereunder. The ends of the flashing 40, beyond the sides of the drip pan 12, are turned upwardly thereagainst forming the flanges 42, and the portion 41 is slit at a point inwardly from its ends and the end portions beyond said slits are turned upwardly, as at 44. A vertical baffle 45 is secured along one edge to the adjacent edges of portions 44 and 41, said baffle 45 extending normal thereto, as shown in Figure 3. Thus any moisture within or dripping upon the corner post of drip pan 12 will be prevented by the flanges 42 and 44 from draining from the drip pan outwardly of the baffle 45.

In Figure 3 baffle 45 is shown as formed from flat plate secured along one edge to the edges of portions 41 and 44 and functions precisely as the flange 35 of angle 36.

5 A similar arrangement is provided for that portion of the drip pan which extends over the doorway. On a line adjacent each side of said doorway, portion 41 is slit and the material between the slits bent upwardly, as at 46. Likewise 10 a similar arrangement is provided when the lower edge of the drip pan passes a post. Of course, baffles 45' are provided similar to baffles 45 and for the same purpose. Consequently the drip pan flashing is provided with the downturned portions 41 to direct moisture from said pan over the top of lining 31 and into flues 7 between the posts, and with upturned portions 44 and 46 to prevent moisture from said drip pan from contacting any post, or dripping into said doorway, 15 and with baffles to prevent movement of the moisture longitudinally of the car on portions 41. 20

It is thus apparent that there is provided a very effective flashing arrangement for overhead bunker refrigerator cars which will positively prevent any moisture dripping in the doorway when the doors are open, or contacting the door posts of the car.

The accompanying drawings illustrate the preferred form of the invention, though it is to be understood that the invention is not limited to the exact details of construction shown and described, as it is obvious that various modifications thereof, within the scope of the claims, will occur to persons skilled in the art.

35 I claim:

1. A flashing for a refrigerator car having a wall element including spaced posts, a doorway and flues, and a substantially horizontal drip pan element having one margin thereof adjacent said wall, said flashing comprising a body portion adapted to be secured to one of said elements and provided with upwardly extending portions adapted to prevent moisture from said drip pan contacting said posts and dripping into said doorway and with spaced downwardly extending portions adapted to direct moisture from said drip pan into said flues.

2. A flashing as defined in claim 1 including a baffle secured to the adjacent edges of said upwardly and downwardly extending portions and projecting normally therefrom to confine the moisture to said downwardly extending portions.

3. A flashing for a refrigerator car having a doorway and spaced posts in substantially the same vertical plane, said flashing comprising a continuously extending gutter-like body portion and a continuously extending piece issuing from an edge of said gutter-like portion adapted to be secured to said posts in a horizontal plane above said doorway, said continuous piece being turned upwardly adjacent each post and over said doorway to prevent moisture from said gutter-like portion flowing against said posts or into said doorway.

65 4. A flashing as set forth in claim 3 and baffles secured to the adjacent edges of said upwardly turned portions of said piece and extending normal thereto.

5. A flashing for a refrigerator having a wall provided with spaced posts and a doorway, a drip pan and a flue; said flashing comprising a continuously extending body portion adapted for attachment to said drip pan and having a portion extendable into said flue, said latter portion provided with means extendable across and above

said doorway and adjacent said posts to prevent moisture dripping into said doorway and against said posts.

6. A flashing for a refrigerator car having a drip pan and a flue; said flashing comprising a continuously extending body portion adapted to be carried by said car and formed with a gutter-like part adapted to discharge into said flue, and a continuously extending counter flashing having a margin for attachment to said drip pan and having a portion extendable into said gutter-like part whereby liquid on said drip pan is directed into said flue.

7. A flashing for a refrigerator having a wall including lining means and a flue forming part of said wall, a doorway in said wall, a refrigerant container adjacent said wall above the upper edge of said lining, and a drip pan below said container extending to said wall above said lining; said flashing comprising a continuously extending body portion adapted to be carried by said wall and adapted to discharge into said flue, and a continuously extending counterflashing having a margin for attachment of said drip pan and having a portion extendable into said body portion whereby liquid from said container is directed into said flue, said flashing having a portion ex-

tendable across and above said doorway to prevent moisture dripping into said doorway.

8. A flashing for a refrigerator car having a wall and a flue forming part of said wall, a doorway in said wall, a refrigerant container adjacent said wall, and a drip pan below said container extending to said wall; said flashing comprising a continuously extending body portion adapted to be carried by said wall and formed with a gutter-like part adapted to discharge into said flue, and a continuously extending counterflashing having a margin for attachment to said drip pan and having a portion extendable into said gutter-like part whereby liquid from said container is directed into said flue, said flashing having a portion extendable across and above said doorway to prevent moisture dripping into said doorway.
